Primary Examiner — George D. Kirschbaum*Assistant Examiner* — Kathleen L Jones(74) *Attorney, Agent, or Firm* — Workman Nydegger(57) **CLAIM**

The ornamental design for an electronic communication device, as shown and described.

DESCRIPTION

1. Electronic communication device

1.1 is a perspective view of an electronic communication device.

1.2 is a top plan view thereof.

1.3 is a front elevation view thereof.

1.4 is a side elevation view thereof; and,

1.5 is a bottom plan view thereof.

The broken lines showing portions of the electronic communication device are included for the purpose of illustration only and form no part of the claimed design.

1 Claim, 5 Drawing Sheets(56)
